HAIR WAVING DEVICE

Charles K. Thau, Brooklyn, N. Y.

Application December 22, 1934, Serial No. 758,721

14 Claims. (Cl. 132—41)

My invention relates to hair waving devices and refers more particularly to such devices of the type capable of use by a woman for waving her own hair, and to that kind of such devices which are adapted to form two waves in the hair at the same time with such superposed waves undulating in different directions; for example, with one of these waves undulating outwardly and inwardly, while the other wave undulates laterally, these two waves merging together into a single compound or composite wave of the desired conformation, this wave thus being, in general, of the Marcel type.

Commonly heretofore, in order to produce the lateral component of the compound wave as a whole, toothed comb-like members have been used which are slidably movable longitudinally relatively to one another. In such instances, the hair-engaging teeth have a tendency to become entangled in the hair, to disarrange the wave formed in the hair, and also to break some of the hairs.

In carrying out my invention, I have dispensed with comb teeth, or anything similar thereto. In my hair waving device I employ two pairs of bowed smooth resilient clamping bars which are suitably spaced apart, one pair above the other, and between the opposed bars of which the hair is firmly but resiliently gripped and held. When the bars of these pairs are brought together they clamp a tress of hair between them.

Intermediately of these two clamping bars, and for the most part inwardly relatively thereto, the hair is again clamped and firmly held between a cooperating pair of opposed resilient bars, the clamping surfaces of which have interfitting complementary rounded corrugations of undulatory form, extending in a series along the length of these two clamping bars, which bow outwardly to a less extent than the two mentioned spaced pairs of clamping bars.

Two outermost pairs of hair-guiding bars are provided with these pairs spaced respectively above and below the mentioned two spaced pairs of clamping bars. The bars of each of these outermost pairs are spaced from each other sufficiently that the hair is not gripped or clamped tightly between them when the clamping bars of the mentioned three pairs thereof are in clamping engagement with the hair. These guiding bars of each pair thereof thus permit the hair to be drawn between them as the hair is clamped between the clamping bars.

These hair-guiding bars are also resilient and bow outwardly to a somewhat less extent than

does the mentioned intermediate or central corrugated clamping bars. Thus all of the mentioned five pairs of bars are disposed transversely in zig-zag fashion, or in outward and inward offset relation relatively to any next adjacent pair of bars. This just mentioned relation of the pairs of bars to each other produces the outwardly and inwardly undulating component of the composite wave.

The corrugated pair of clamping bars is slideable longitudinally relatively to the above mentioned two spaced pairs of clamping bars. This sliding movement is effective to produce the laterally undulating component of the composite or compound wave in the hair while the hair is clamped between the opposed clamping bars of each of the three mentioned pairs thereof. This lateral component of undulation in the hair is thus superimposed upon the above mentioned outward and inward undulatory component of the complete wave thus formed in the clamped tress of hair.

My invention includes further features of construction and combinations of parts, as will be clear from the following description and appended claims, taken in connection with the accompanying drawing illustrating one form of my invention and in which similar parts are designated by similar numerals.

Figure 1 is a plan view showing one form of the device of my invention as clamped upon a tress of hair.

Figure 2 is a side edge view looking upward in Figure 1, but with the two hinged-together parts of the device in a partly open position.

Figure 3 is a longitudinal section on the line 3—3 of Figure 1.

Figures 4, 5, and 6, are similar transverse sections taken respectively on the lines 4—4, 5—5, 40 and 6—6 of Figure 3.

Figure 7 is a broken longitudinal section taken substantially on the bent line 7—7 of Figure 2.

Figure 8 is a broken plan view similar to Figure 1, but showing the relatively slideable pair of bar members as positioned to produce the lateral wave component in the clamped tress of hair, as there indicated.

The particular form of the hair waving device of my invention shown in the accompanying drawing comprises two similar main resilient sheet metal frame members, one of which is an inner frame member and the other of which is an outer frame member. The inner frame member has upper and lower hair-guiding bars 10 and 55

11, the ends of which are connected together by cross bars 12 and 13.

5 The guide bars 10 and 11 are flat in cross section, relatively narrow in width, and are similarly slightly bowed outwardly. The end cross bar 12 is shown as being relatively wide, in order to contribute adequate strength and stiffness, for reasons which will be clear later, while at the other end the cross bar 13 is of somewhat less width.

10 The outer frame part is substantially similar to the above described inner frame part. This outer frame part has similarly slightly outwardly bowed hair-guiding bars 14 and 15, the opposite ends of which are connected together by cross bars 16 and 17, of which the cross bar 16, for strength and stiffness, is of greater width than the other end cross bar 17.

15 The outer upper guide bar 14 overlies and cooperates with the inner upper guide bar 11 and is slightly spaced in substantially parallel relation therewith, while the outer lower guide bar 15 has a similar relationship with the inner lower guide bar 11. The inner guide bars 10 and 11 come next to the scalp and it will be noted that the longitudinal curvature of these bars is less than the curvature of the head of a person, so that thereby the opposite ends of the device will conveniently stand out somewhat from the head. The tress of hair which is to be waved extends transversely 20 through the middle portion of the device, as is clearly shown in Figures 1, 2, and 3.

25 The outer edge of the wider end cross bar 12 of the inner frame part is provided with four outwardly turned hinge knuckles 18-18, while the wider end cross bar 16 of the outer frame part is similarly provided with four inturned hinge knuckles 19-19 which are disposed transversely inward respectively from the other hinge knuckles 18-18. The two adjacent intermediate hinge 30 knuckles 19-19 are spaced apart for a purpose described later. These two sets of hinge knuckles 18-18, and 19-19 are pivotally connected together by a pintle or pivot pin 20. Thus the described inner and outer frame parts or members 35 are hinged together at one end of the device.

40 The free end of the outer frame part, in line with its end bar 17, is provided at its upper and lower edges with similar substantially S-shaped resilient catch members 21-21, adapted to snap over the adjacent edges of the inner frame part adjacent to the opposite ends of its end bar 13, thereby releasably maintaining the outer guide bars 14 and 15 in cooperative opposed hair-guiding relation with the inner guide bars 10 and 11 45 respectively, as well as also maintaining opposed clamping bars of a plurality of pairs thereof in clamping position upon the hair, as is to be described.

46 A pair of similar upper and lower rather widely spaced clamping bars 22 and 23 are fixedly carried at their respective opposite ends by the end bars 12 and 13 of the main inner frame member. These clamping bars 22 and 23 are respectively spaced transversely inward from the guiding bars 10 and 11 of the main frame member, but to a considerably less extent than the distance which these clamping bars 22 and 23 are spaced from each other. This relatively wider spacing between the clamping bars 22 and 23 is for a purpose described later. These clamping bars 22 and 23 are smooth, transversely flat, relatively narrow, and bow outwardly to a considerably greater extent than do the guiding bars 10 and 11 of the inner main frame member, as is clearly shown in 50 Figures 2, 3, and 5, and are resilient.

55 In the particular device shown in the drawing, these clamping bars 22 and 23 form a supplemental inner frame together with end bars 24 and 25. The wider end bar 24, at the hinge end of the device, is divided into two lateral parts, for a purpose described later, while the cross bar 25 at the other end of the device connects together these ends of the clamping bars 22 and 23.

60 The two-part, or divided, wider cross bar 24 of this inner supplemental frame overlies and is firmly secured to the end cross bar 12 of the main frame member, such as by means of a pair of rivets, as indicated in Figure 7, while the continuous other cross bar 25 of this supplemental inner frame overlies and is similarly secured to 65 the end bar 13 of the inner main frame part.

66 The end cross bars 16 and 17 of the outer main frame member respectively fixedly carry the opposite ends of outer upper and lower clamping bars 26 and 27 which have a longitudinally bowed curvature matching that of the inner clamping bars 22 and 23, and are outwardly opposed thereto, in alignment therewith.

70 In the particular device shown, these outer clamping bars 26 and 27 have end bars 28 and 29, forming therewith an outer supplemental frame part, which is similar to the above described inner supplemental frame part. The wider end bar 28, which is at the hinge end of the device, is divided into two lateral parts, while the other end bar 29 is continuous and connects together the ends of these outer clamping bars 26 and 27.

75 The divided end bar 28 underlies and is fixedly secured to the end bar 16 of the main outer frame member, such as by means of rivets, as indicated in Figure 1, while the continuous end cross bar 29 underlies and is similarly secured to the end cross bar 17 of the mentioned outer frame member, as is also indicated in Figure 1. These outer clamping bars 26 and 27 are of similar cross section to the inner clamping bars 22 and 23, which they respectively overlie, and are also similarly resilient.

80 The contour of the curvature of the inner clamping bars 22-23 and of the outer clamping bars 26-27, is such relatively to each other, in 45 the two cooperating pairs thereof, that the inner faces of the outer clamping bars 26 and 27 will abut against the outer faces of the inner clamping bars 22 and 23, respectively, when there is no tress of hair interposed between them. 50 When a tress of hair is thus interposed, the resiliency of the clamping bars permits them to be sprung apart, and thus resiliently but firmly grip the hair between them, as shown in the drawing, particularly in Figures 3 and 5.

85 When the device has its main frame members in their closed together and latched position, as shown in Figures 1, 3 to 6 inclusive, and 8, the tress of hair is also clamped along a line midway between the upper pair of cooperating 60 clamping bars 22-26 and the lower pair of cooperating clamping bars 23 and 27, by means of another opposed and aligned cooperating pair of intermediate resilient inner and outer clamping bars 30 and 31, of which the inner clamping bar 30 is carried by the inner main frame member, while the outer clamping bar 31 is carried by the outer main frame member.

90 These clamping bars 30 and 31 extend longitudinally of the device from end to end thereof 70 and are longitudinally bowed outwardly to a somewhat greater extent than are the above described pairs of cooperating guiding bars 10, 14, and 11, 15, but with these clamping bars 30-31 are bowed outwardly to a much less extent than 75

are the above described pairs of clamping bars 22, 26, and 23, 27.

Each of these intermediate clamping bars 30—31 is corrugated along and substantially throughout its length. These corrugations are of a smooth gradually rounded undulatory form, are complementary to each other as to the respective bars 30 and 31, and are proportioned and disposed so as to interfit or interengage with one another when these two bars are brought together in the closed clamping condition of the device, as is shown most clearly in Figure 3.

Without a tress of hair clamped in the device, the relative contour of curvature of these clamping bars 30 and 31 is such that they will come into abutting contact with one another substantially throughout their length and especially throughout their intermediary or middle portions. With a tress of hair clamped between them these bars will be resiliently sprung apart, thereby firmly but resiliently clamping the interposed hair, as is most clearly shown in Figures 3 and 5 of the drawing.

This opposed pair of cooperating corrugated clamping bars are mounted so as to be capable of longitudinal sliding movement together as a unit, and to a definitely limited desired extent. In the closed and clamping position of the hinged parts of the device, this unitary sliding movement of these clamping bars 30 and 31 is assured by reason of the interengaging and interfitting relationship of their corrugations, as will be clear from Figure 3; but when the opposed parts of the device are in open position as shown in Figure 2, these corrugated clamping bars 30 and 31 may be slidably adjusted independently of each other, if so desired for any reason.

The inner corrugated clamping bar 30 has uncorrugated substantially straight portions adjacent to each of its ends. At the open end of the device, opposite to its hinge end, the uncorrugated portion of this bar 30 is slidably guided through a guide loop therefor formed between the adjacent end cross bar 13 of the inner main frame member and the overlying end cross bar 25 of the inner supplemental frame member, as is most clearly shown in Figure 6. Beyond the cross bar 13 the end of this clamping bar 30 is provided with a rounded eye-shaped head 32.

At the hinge end of the device, the uncorrugated portion of the clamping bar 30 is guided laterally between the spaced ends of the divided inner supplemental frame end bar 24, as shown in Figures 4 and 7. This end of the clamping bar 30 has an outturned lug 33 formed thereon, which at the limit of outward movement of this bar 30 is adapted to abut against a small stop lug 34 formed upon one of the end bar parts 24, so as to overlie the adjacent uncorrugated portion of the bar 30 and thus also retain the latter in place.

The outer corrugated clamping bar 31, which is opposed to and cooperates with the inner corrugated clamping bar, 30, is similarly mounted for longitudinal sliding movement. At the latching end of the device, an uncorrugated substantially straight portion of this bar 31 is slidably guided through a guide loop therefor formed between the adjacent end cross bar 17 of the outer main frame member and the underlying end cross bar 29 of the outer supplemental frame member, as shown in Figure 6 and indicated in other figures of the drawing.

A tongue or prong 35 is turned inward from this end of the bar 31 and is adapted, in the closed

position of the device, to engage with the free side of the rounded head 32 of the inner corrugated bar 30, as shown in the drawing, particularly in Figure 3 by the full lines.

A handle eye 36 is fixedly secured, for example 5 by means of rivets, as indicated in Figure 1, upon the upper side of the end portion of the bar 31 which projects beyond the outer main frame member cross bar 17.

The attached portion of this handle eye or 10 ring 36 is adapted to abut against the edge of the main frame cross bar 17, for thereby limiting the inwardly sliding movement of this outer corrugated bar 31, which consequently limits the inward sliding movement of the inner corrugated 15 bar 30, by reason of the mentioned interengagement of these two slidably corrugated bars.

At the hinge end of the device, an uncorrugated substantially straight portion of this outer corrugated clamping bar 31 is laterally guided 20 between the spaced ends of the divided outer supplemental frame end bar 28, as shown in the drawing, particularly in Figure 4.

A small stop lug 37 formed upon one of the parts of the divided end bar 28 underlies the adjacent 25 uncorrugated portion of the bar 31, so as to maintain the latter in place. This end of the clamping bar 31 has an inturned lug 38 formed thereon, which at the limit of the outward movement of this bar 31 will abut against the lug 37, 30 which thus forms a limiting stop for this bar 31 in the outward movement of the latter.

This outward or withdrawn position of the two cooperatively opposed corrugated clamping bars 30 and 31 is indicated, at each of the opposite 35 ends of the device, by the broken lines in Figure 3. The gap between the two intermediate hinge knuckles 19—19 assures clearance for the adjacent ends of the corrugated clamping bars 30 and 31. 40

My invention can be carried out in a slightly modified form of the device by making the inner clamping bars 22 and 23 in the same piece of material with the inner main frame part, in which case, the opposite ends of these clamping bars 22 45* and 23 would be joined integrally with the main frame end cross bars 12 and 13. In a similar manner, the outer clamping bars 26 and 27 can be made in the same piece of material with the outer main frame member with their ends respectively integrally joined to the end cross bars 16 and 17 of this outer main frame member. 50

In such case, the inner clamping bars 22 and 23 can be slightly stretched or drawn in order 55 to compensate for the slightly greater length of these bars as compared with the guide bars 10 and 11; and a similar procedure can be followed for the outer clamping bars 26 and 27 as compared with the slightly less length of the 60 guiding bars 14 and 15.

It is to be noted that, for the most part, the entire device of my invention can be readily manufactured by simple stamping, or pressing, operations. The device of my invention may be 65 formed of any suitable material, for example, as sheet steel, or brass. The size and proportions of my hair waving device may conveniently be substantially the same as shown in my accompanying patent drawing. 70

It will be noted that the device is symmetrical transversely in vertical planes, thereby rendering it capable of equally convenient use upon either side of the user's head.

The manner of use and operation of the above 75

described hair waving device of my invention are as follows:

With the two hingedly connected parts or elements of the device at open position, substantially as shown in Figure 2, or somewhat more widely opened if desired, the inner element of the device may be readily passed inwardly from and between a lifted or separated tress of hair and the scalp, as there shown. Then the free ends of 10 the hinged parts of the device may be simply pressed together upon this interposed tress of hair, with the resilient snap catches 21—21 then in latching engagement with the opposite edges of 15 the inner main frame member adjacent to the end bar 13 of the latter, as shown in Figures 1, 3, and 6.

The device will then be clamped upon this tress of hair substantially in the position of the device shown in Figure 1. When the two parts of the 20 device are thus clamped and latched together, the hair will be bent into a wave in vertical planes transversely of the device and along the length of the hair, as shown in Figure 5, indicated in Figure 3, and corresponding with Figure 1.

25 The corrugated clamping bars 30 and 31 are now moved longitudinally from the full line position thereof shown in Figures 1 and 3, to the partially shown broken line position of Figure 3, by pulling on the ring-shaped handle 36. This 30 movement of the pair of corrugated clamping bars 30 and 31 moves the clamped hair from the straight line position thereof as shown in Figure 1, and forms therein the lateral wave component shown in Figure 8.

35 This lateral wave component extends between the upper pair of clamping bars 22 and 26, and the lower pair of such bars 23 and 27, by both of which latter pairs of bars the hair is clamped and held. The hair has sufficient looseness and 40 elasticity for the formation of this lateral wave without straining the hair.

It is also to be noted that the clamping of the device upon the hair as above described causes small waves or ripples to be produced in the hair 45 transversely of the clamped tress thereof, and longitudinally of the device, by the corrugated form of the clamping surfaces of the bars 30—31, as is clearly shown in Figure 3.

The device is now left in place upon the clamped 50 and waved tress of hair for an ascertained predetermined length of time, until the wave produced therein has become set and self-sustaining. Then the outer part of the device is swung to an open position, merely by pulling it away from the 55 inner part. The curved resilient catch at 21—21 is adapted to yield apart so as to pass outwardly beyond the opposite edges of the inner frame member. With the device thus in open condition it may be readily withdrawn and removed from 60 the hair and may be reapplied to the hair at another place if so desired.

It will be noted, as already described, that three substantially different wave components are formed in the complete composite hair wave 65 considered as a whole.

It is to be noted that, whenever desired, the swinging parts of the device may be clamped upon a tress of hair with the slideable corrugated pair of clamping bars 30—31 already previously pulled 70 out to the broken line position of Figure 3. When the hair has been thus clamped, these corrugated bars may then be pushed in, by means of the handle 36. This will form a lateral wave component in the opposite direction to that shown in 75 Figure 8. Thus a lateral wave in one direction

at one place and in the opposite direction at another place may be produced in the hair, if so desired.

It is to be further noted, besides being convenient and economical of manufacture, that the 5 hair waving device of my invention is convenient in use, that it does not abrade, strain, break, or in any other way injure the hair, and in fact that it has many valuable attributes which make it in several respects a distinct improvement over 10 other heretofore commonly used hair waving devices which are in general more or less similar.

It is obvious that various modifications may be made in the construction shown in the drawing and above particularly described, within the principle and scope of my invention as defined in the 15 appended claims.

I do not limit myself to the particular size, shape, number or arrangement of parts as particularly disclosed and described, as these are 20 given simply as a means for clearly describing the device of my invention.

What I claim is:—

1. In a hair waving device, in combination, a pair of aligned and opposed cooperating clamping 25 bars having their adjacent hair-clamping faces provided with curved interengaging complementary corrugations, with such corrugations forming an undulatory series thereof extending longitudinally along said bars, and two similar pairs 30 of clamping bars spaced from said pair of corrugated clamping bars at opposite sides thereof and disposed out of transverse alignment therewith.

2. In a hair waving device, in combination, a pair of aligned and opposed cooperating clamping 35 bars having their adjacent hair-clamping faces provided with curved interengaging complementary corrugations, with such corrugations forming an undulatory series thereof extending longitudinally along said bars, and two similar pairs 40 of clamping bars spaced from said pair of corrugated clamping bars at opposite sides thereof and disposed out of transverse alignment therewith, said pair of corrugated clamping bars being mounted for longitudinal shifting movement relatively to said two pairs of clamping bars.

3. In a hair waving device, in combination, a pair of aligned and opposed cooperating clamping bars having their adjacent hair-clamping faces provided with curved interengaging complementary corrugations, with such corrugations forming an undulatory series thereof extending longitudinally along said bars, two similar pairs of 50 aligned and opposed clamping bars spaced from said pair of corrugated clamping bars at opposite 55 sides thereof and disposed out of transverse alignment therewith, said pair of corrugated clamping bars being mounted for longitudinal shifting movement relatively to said two pairs of clamping bars, and two similar pairs of aligned and opposed 60 hair-guiding bars respectively spaced from said two pairs of clamping bars beyond them from said corrugated pair of clamping bars and disposed out of transverse alignment with said two pairs of clamping bars toward the same side thereof 65 as said pair of corrugated clamping bars.

4. In a hair waving device, in combination, two similar pairs of horizontally extending vertically spaced outwardly bowed aligned and opposed cooperating clamping bars, an intermediate pair of 70 horizontally extending aligned and opposed cooperating clamping bars between said spaced pairs of clamping bars and bowed outwardly to a less extent, said intermediate pair of clamping bars having their adjacent hair-clamping faces 75

provided with curved interengaging complementary corrugations, with such corrugations forming an undulatory series thereof extending longitudinally along said bars, and two pairs of horizontally extending aligned and opposed hair-guiding bars respectively spaced above and below beyond said two pairs of clamping bars and bowed outwardly to a less extent than said pair of corrugated bars, said pair of corrugated clamping bars being mounted for limited longitudinal sliding movement relatively to said two pairs of clamping bars and said two pairs of hair-guiding bars.

5. In a hair waving device, in combination, a pair of aligned and opposed inner and outer cooperating clamping bars having their adjacent hair-clamping faces provided with curved interengaging complementary corrugations, with such corrugations forming an undulatory series thereof extending longitudinally along said bars, means including a hinge adapted for connecting said bars together at one end of the device so as to enable said outer clamping bar to be swung inwardly and outwardly relatively to said inner clamping bar, thereby being adapted for clamping and unclamping hair interposed between said hair-clamping faces, and releasable catch means at the other end of the device adapted for clamping said bars together and for releasing them for relative swinging movement.

6. In a hair waving device, in combination, a pair of aligned and opposed inner and outer cooperating clamping bars having their adjacent hair-clamping faces provided with curved interengaging complementary corrugations, with such corrugations forming an undulatory series thereof extending longitudinally along said bars, two similar pairs of aligned opposed inner and outer clamping bars spaced from said pair of corrugated clamping bars at opposite sides thereof and disposed out of transverse alignment therewith, end members respectively fixedly connecting together each of the opposite ends of the outer bars and of the inner bars of said two similar pairs of clamping bars, a hinge joint connection between said connecting members at one end of the device, and releasable catch means at the other end of the device adapted for clamping said inner and said outer clamping bars together and for releasing them to provide for their relative inwardly and outwardly swinging movement.

7. In a hair waving device, in combination, a pair of aligned and opposed inner and outer cooperating clamping bars having their adjacent hair-clamping faces provided with curved interengaging complementary corrugations, with such corrugations forming an undulatory series thereof extending longitudinally along said bars, two similar pairs of aligned opposed inner and outer clamping bars spaced from said pair of corrugated clamping bars at opposite sides thereof and disposed out of transverse alignment therewith, end members respectively fixedly connecting together each of the opposite ends of the outer bars and of the inner bars of said two similar pairs of clamping bars, said inner corrugated clamping bar being mounted for limited longitudinal sliding movement upon said connecting members belonging to said inner bars of said two similar pairs of clamping bars, said outer corrugated clamping bar being mounted for limited longitudinal sliding movement upon said connecting members belonging to said outer bars of said two similar pairs of clamping bars, a hinge joint connection between said connecting members at one end of the

device, and releasable catch means at the other end of the device adapted for clamping said inner and said outer clamping bars together and for releasing them to provide for their relative inwardly and outwardly swinging movement.

8. In a hair waving device, in combination, two spaced similar pairs of aligned and opposed inner and outer cooperating hair-guiding bars, two spaced similar pairs of aligned and opposed inner and outer cooperating clamping bars between said pairs of hair-guiding bars and spaced therefrom, inner cross bars respectively fixedly connecting together the opposite ends of said inner hair-guiding bars and respectively fixedly connected to the opposite ends of said inner clamping bars, outer cross bars respectively fixedly connecting together the opposite ends of said outer hair-guiding bars and respectively fixedly connected to the opposite ends of said outer clamping bars, an intermediate pair of aligned and opposed inner and outer cooperating clamping bars between said two pairs of clamping bars in spaced relation therewith and having their adjacent hair-clamping faces provided with curved interengaging complementary corrugations, with such corrugations forming an undulatory series thereof extending longitudinally along said bars, said inner corrugated bar being mounted for limited longitudinal sliding movement upon said inner cross bars, said outer corrugated bar being mounted for limited longitudinal sliding movement upon said outer cross bars, a hinge joint connection between said inner and outer cross bars at one end of the device, and releasable catch means at the other end of the device adapted for clamping all of the opposed inner and outer clamping bars upon an interposed tress of hair while at the same time maintaining said inner and outer hair-guiding bars in opposed hair-guiding position, all of said pairs of bars being disposed transversely of the clamped device in alternating zig-zag fashion.

9. In a hair waving device, in combination, two similar pairs of horizontally extending vertically spaced outwardly bowed aligned and opposed inner and outer cooperating clamping bars, an intermediate pair of horizontally extending aligned and opposed inner and outer cooperating clamping bars between said spaced pairs of clamping bars and bowed outwardly to a less extent, said intermediate pair of clamping bars having their adjacent hair-clamping faces provided with curved interengaging complementary corrugations, with such corrugations forming an undulatory series thereof extending longitudinally along said bars, two pairs of horizontally extending aligned and opposed inner and outer cooperating hair-guiding bars respectively spaced above and below beyond said two pairs of clamping bars and bowed outwardly to a less extent than said pair of corrugated bars, inner cross bars respectively fixedly connecting together the opposite ends of said inner hair-guiding bars and respectively fixedly connected to the opposite ends of said inner clamping bars of said two spaced pairs thereof, outer cross bars respectively fixedly connecting together the opposite ends of said outer hair-guiding bars and respectively fixedly connected to the opposite ends of said outer clamping bars of said two spaced pairs thereof, said inner corrugated bar being mounted for limited longitudinal sliding movement upon said inner cross bars, said outer corrugated bar being mounted for limited longitudinal sliding movement upon said outer cross bars, a hinge joint

connection between said inner and outer cross bars at one end of the device, and releasable catch means at the other end of the device adapted for clamping all of the opposed inner and outer clamping bars upon an interposed tress of hair while at the same time maintaining said inner and outer hair-guiding bars in opposed hair-guiding position.

10. In a hair waving device, in combination, a pair of aligned and opposed inner and outer cooperating clamping bars having their adjacent hair-clamping faces provided with curved inter-engaging complementary corrugations, with such corrugations forming an undulatory series thereof extending longitudinally along said bars, means including a hinge adapted for connecting said bars together at one end of the device so as to enable said outer clamping bar to be swung inwardly and outwardly relatively to said inner clamping bar, thereby being adapted for clamping and unclamping hair interposed between said hair-clamping faces, and releasable catch means at the other end of the device adapted for clamping said bars together and for releasing them for relative swinging movement, said corrugated clamping bars being transversely flat with rounded bends therein forming said corrugations and being resilient.

11. In a hair waving device, in combination, a pair of aligned and opposed inner and outer cooperating clamping bars having their adjacent hair-clamping faces provided with curved inter-engaging complementary corrugations, with such corrugations forming an undulatory series thereof extending longitudinally along said bars, two pairs of aligned opposed inner and outer clamping bars spaced from said pair of corrugated clamping bars at opposite sides thereof and disposed out of transverse alignment therewith, end members respectively fixedly connecting together each of the opposite ends of the outer bars and of the inner bars of said two similar pairs of clamping bars, a hinge joint connection between said connecting members at one end of the device, and releasable catch means at the other end of the device adapted for clamping said inner and said outer clamping bars together and for releasing them to provide for their relative inwardly and outwardly swinging movement, all of said clamping bars being transversely flat and being resilient, said corrugated clamping bars having rounded bends therein forming said corrugations.

12. In a hair waving device, in combination, a pair of aligned and opposed inner and outer cooperating clamping bars having their adjacent hair-clamping faces provided with curved inter-engaging complementary corrugations, with such corrugations forming an undulatory series thereof extending longitudinally along said bars, two similar pairs of aligned opposed inner and outer clamping bars spaced from said pair of corrugated clamping bars at opposite sides thereof and disposed out of transverse alignment therewith, end members respectively fixedly connecting together each of the opposite ends of the outer bars and of the inner bars of said two similar pairs of clamping bars, said inner corrugated clamping bar being mounted for limited longitudinal sliding movement upon said connecting members belonging to said inner bars of said two similar pairs of clamping bars, said outer corrugated clamping bar being mounted for limited longitudinal sliding movement upon said connecting members belonging to said outer bars

of said two similar pairs of clamping bars, a hinge joint connection between said connecting members at one end of the device, and releasable catch means at the other end of the device adapted for clamping said inner and said outer clamping bars together and for releasing them to provide for their relative inwardly and outwardly swinging movement, said corrugated clamping bars being transversely flat with rounded bends therein forming said corrugations and being resilient.

13. In a hair waving device, in combination, two spaced similar pairs of aligned and opposed inner and outer cooperating hair-guiding bars, two spaced similar pairs of aligned and opposed inner and outer cooperating clamping bars between said pairs of hair-guiding bars and spaced therefrom, inner cross bars respectively fixedly connecting together the opposite ends of said inner hair-guiding bars and respectively fixedly connected to the opposite ends of said inner clamping bars, outer cross bars respectively fixedly connecting together the opposite ends of said outer hair-guiding bars and respectively fixedly connected to the opposite ends of said outer clamping bars, an intermediate pair of aligned and opposed inner and outer cooperating clamping bars between said two pairs of clamping bars in spaced relation therewith and having their adjacent hair-clamping faces provided with curved interengaging complementary corrugations, with such corrugations forming an undulatory series thereof extending longitudinally along said bars, said inner corrugated bar being mounted for limited longitudinal sliding movement upon said inner cross bars, said outer corrugated bar being mounted for limited longitudinal sliding movement upon said outer cross bars, a hinge joint connection between said inner and outer cross bars at one end of the device, and releasable catch means at the other end of the device adapted for clamping all of the opposed inner and outer clamping bars upon an interposed tress of hair while at the same time maintaining said inner and outer hair-guiding bars in opposed hair-guiding position, all of said pairs of bars being disposed transversely of the clamped device in alternating zig-zag fashion, all of the bars of said pairs of bars being transversely flat and being resilient, said corrugated clamping bars having rounded bends therein forming said corrugations.

14. In a hair waving device, in combination, two similar pairs of horizontally extending vertically spaced outwardly bowed aligned and opposed inner and outer cooperating clamping bars, an intermediate pair of horizontally extending aligned and opposed inner and outer cooperating clamping bars between said spaced pairs of clamping bars and bowed outwardly to a less extent, said intermediate pair of clamping bars having their adjacent hair-clamping faces provided with curved interengaging complementary corrugations, with such corrugations forming an undulatory series thereof extending longitudinally along said bars, two pairs of horizontally extending aligned and opposed inner and outer cooperating hair-guiding bars respectively spaced above and below beyond said two pairs of clamping bars and bowed outwardly to a less extent than said pair of corrugated bars, inner cross bars respectively fixedly connecting together the opposite ends of said inner-hair-guiding bars and respectively fixedly connected to the opposite ends of said inner clamping bars of said two

spaced pairs thereof, outer cross bars respectively fixedly connected together the opposite ends of said outer hair-guiding bars and respectively fixedly connected to the opposite ends of 5 said outer clamping bars of said two spaced pairs thereof, said inner corrugated bar being mounted for limited longitudinal sliding movement upon said inner cross bars, said outer corrugated bar being mounted for limited longitudinal sliding movement upon said outer cross bars, a hinge joint connection between said inner and outer cross bars at one end of the device,

and releasable catch means at the other end of the device adapted for clamping all of the opposed inner and outer clamping bars upon an interposed tress of hair while at the same time maintaining said inner and outer hair-guiding bars in opposed hair-guiding position, all of the bars of said pairs of bars being transversely flat and being resilient, said corrugated clamping bars having rounded bends therein forming said corrugations. 10
